UNITED STATES PATENT OFFICE.

EMIL NOPPEL, OF PHILADELPHIA, PENNSYLVANIA.

SHOE-PULL.

SPECIFICATION forming part of Letters Patent No. 592,819, dated November 2, 1897.

Application filed September 4, 1896. Serial No. 604,830. (No model.)

To all whom it may concern:

Be it known that I, EMIL NOPPEL, a citizen of the United States, residing in the city and county of Philadelphia, State of Pennsylvania, have invented a new and useful Improvement in Shoe-Pulls, which improvement is fully set forth in the following specification and accompanying drawings.

My invention relates to an improvement in a device adapted for grasping an article of footwear in order to conveniently draw the same on the foot; and it consists in providing such device with novel means, as herein-after described, for engaging with the heel of the shoe, thus preventing the slipping of the implement when upward draft is exerted on the same.

Figure 1 represents a side elevation of a shoe-pull embodying my invention. Fig. 2 represents a rear view thereof.

Similar letters of reference indicate corresponding parts in the two figures.

Referring to the drawings, A designates a shoe-horn having on the rear thereof the ear B, on which is pivoted the lever C, the same being provided with a suitable handle at its upper end and with the jaw D at its lower end, the latter being opposite to the corresponding portion of the horn. Connected with the ear B is the arm or grip E, which projects laterally from said ear and occupies a position below the handle of the lever C. Bearing against the lever C and the handle E is a spring F, whose tendency is to hold the jaw D from the horn A, as shown in Fig. 1.

G designates a leg which depends from the lever C or jaw D and has at its lower end the foot F, which is so disposed as to engage with the heel of the shoe to be drawn on the foot.

The operation is as follows, the position of the parts being shown in Fig. 1: The device is properly grasped and the rear wall of the article of footwear, say a shoe, is received

between the horn A and the jaw D. By properly pressing the lever C toward the grip the jaw D is forced toward the horn A, so that the contiguous portion of the shoe is tightly grasped. At the same time the foot E is directed underneath the heel of the shoe and placed thereagainst, in which position of parts the device is drawn upwardly and the shoe thus conveniently fitted on the foot. By releasing the handle of the lever the jaw separates from the wall of the shoe, and the device may be readily removed, it being noticed that the foot F recedes from the heel of the shoe with the returning motion of the jaw.

It will also be noticed that during the operation of the implement the horn is within the shoe and thus assists the foot to enter the same.

Having thus described my invention, what I claim as new, and desire to secure by Letters Patent, is—

1. A shoe-pull consisting of a horn, a lever pivoted to said horn, a handle on said lever extending rearwardly, a jaw on said lever, a grip extending rearwardly from said horn and toward which said handle is adapted to move, and a leg depending from said lever below said grip and provided with a foot adapted to extend beneath the heel of a shoe.

2. A shoe-pull consisting of a horn, an ear on said horn, a lever pivoted to said ear, a handle on said lever, a jaw on said lever, a grip pivoted to said ear and extending rearwardly therefrom, a spring against the lever and grip and adapted to separate the same, a leg depending from said lever below said jaw and a foot on said leg adapted to extend beneath the heel of a shoe.

EMIL NOPPEL.
